UNITED STATES PATENT OFFICE

151,318

DESIGN FOR A MECHANICAL TOY

Samuel I. Berger, Newark, N. J.

Application May 17, 1947, Serial No. 139,113

Term of patent 14 years

(Cl. D34—15)

To all whom it may concern:

Be it known that I, Samuel I. Berger, a citizen of the United States and a resident of Newark, in the county of Essex and State of New Jersey, have invented a new, original, and ornamental Design for Mechanical Toy, of which the following is a specification, reference being had to the accompanying drawings, forming part thereof, and in which

Fig. 1 is a perspective view of one side of the toy showing my new design which is substantially the same as the other side.

Fig. 2 is a front elevation thereof.

The dominant features of my design are shown in solid lines in the drawing.

I claim:

The ornamental design for a mechanical toy, substantially as shown and described.

SAMUEL I. BERGER.
